UNITED STATES PATENT OFFICE.

OTTO L. WEIMAR, OF PHILADELPHIA, PENNSYLVANIA.

RAILWAY-TIE.

1,087,855.

Specification of Letters Patent. Patented Feb. 17, 1914.

Application filed September 9, 1913. Serial No. 788,896.

To all whom it may concern:

Be it known that I, OTTO L. WEIMAR, a citizen of the United States, residing at Philadelphia, in the county of Philadelphia and State of Pennsylvania, have invented new and useful Improvements in Railway-Ties, of which the following is a specification.

The present invention relates to improvements in railway ties, one of the objects being to construct a tie having an outer body of metal filled with cement or other plastic material and which is also provided with wooden cushion blocks for the reception of the rails, so that the solid construction of the tie will not interfere with the elasticity of the rails.

Another object of the invention is the construction of a tie which shall embody a metallic shell and which is provided with a central partition and cross braces extending from the partition to the opposite ends of the tie, so as to provide the tie with a plurality of compartments each of which will receive a suitable ballast of concrete or the like to impart weight and stability to the tie, so that when the same is arranged upon the roadbed and the earth packed around the tie, the tie will be held effectively against movement in any direction.

A still further object of the invention is the provision of a metallic shell or casing divided into compartments through the medium of bracing elements, certain of said brace members supporting, in connection with the tie, cushion members upon which the rails are adapted to rest. The ends of the ties have secured thereto rail engaging members. The tie is provided with a plurality of adjustable members each having their inner edges formed with rail engaging lips. An adjustable wedge is disposed between the said members of the top so as to provide for the longitudinal adjustment of the said members to bring their lips into contacting engagement with the rails or away from such contact when it is desired to remove the rails from the tie.

With these and other objects in view, the improvement resides in the construction, combination and arrangement of parts set forth in the following specification and falling within the scope of the appended claims.

In the drawing: Figure 1 is a perspective view of a tie constructed in accordance with the present invention, parts being broken

away and parts being shown in section, Fig. 2 is a top plan view of the tie, the top plates or cover, as well as the rail engaging members being removed, Fig. 3 is a longitudinal sectional view on the line 3—3 of Fig. 2, but showing the outer rail engaging member and the top positioned upon the tie and sustaining a rail upon the cushion member of the tie, and Fig. 4 is a transverse sectional view on the line 4—4 of Fig. 2, the top being shown in position.

The tie includes an outer shell or casing 1, the said casing having its body comprising a base 2 and vertically disposed sides 3. The ends 4 of the shell have their vertical edges inturned to provide flanges 5 which are inserted between the sides 3 and which are adapted to be secured to the shell through the medium of removable elements, in the nature of nuts and bolts. The interior of the shell is centrally provided with a transverse partition 6, and extending in opposite directions from the said partition are cross bracing members 7, one of said members being formed with slots to receive the second member, in the well known manner, and the members 7, at their central and meeting portions, are secured through the medium of angular clips 8. The cross brace members 7 are of a width corresponding to the height of the sides 3 of the shell, as is the partition 6, so that the said brace member 7 and the partition 6 divide the shell into a plurality of compartments, within each of which is inserted ballast 9 of sand, concrete, or the like. The cross brace members 7 have their ends flanged longitudinally with relation to the longitudinal plane of the shell, the said flanged ends contacting with the opposite inner faces of the shell and being provided with openings which register with similar openings in the sides 3, the registering openings receiving means in the nature of bolts 10, adjusting nuts 11 and securing nuts 12, the said securing nuts being arranged upon the outer faces of the sides 3. The cross braces at a suitable distance from the ends 4 of the tie are provided with notches or depressions 13 which are arranged in a line with similar notches 14 formed in the sides of the tie, and these notched portions are adapted to receive cushion members 15 which are in the nature of wooden blocks, and which are adapted to receive the base flanges of the rails R.

The ballast within the compartment at

the ends of the tie has anchored therein a plurality of bolt members 16 which project a suitable distance above the tie, and the said bolts are adapted to pass through openings 5 provided in the inclined outer sides 17 of rail engaging blocks 18, the said inclined outer faces of the blocks being formed with depressions or pockets whereby nuts 19 may be screwed upon the threaded ends of the 10 bolt 16, and whereby the blocks 18 are rigidly connected with the tie. The inner face of each of the blocks 18 is shaped to conform to one of the sides of the rail R, and consequently the lower and undercut portion 15 thereof overlies a portion of the cushion member 15.

The side compartments provided by the cross brace members have anchored within their plastic filling or ballast a plurality of 20 upwardly extending bolts 20, the said bolts being arranged in a longitudinal plane parallel with the sides 3 of the shell of the tie, and are positioned inwardly of the said sides a comparatively short distance.

25 The top plates are designated by the numerals 21 and 22 respectively. Each of the plates has its outer end undercut to provide a rail flange engaging lip 23, the said lips, of course, projecting over the rail receiving 30 cushion blocks 15. The sections 22 and 23 are of a width corresponding to that of the shell 1, so as to overlie the filling or ballast within the shell, and the said members are provided adjacent their opposite longitudinal edges 35 with spaced elongated slots 24 through which the bolts 20 project, and co-acting with the said bolts are nuts 25. The tie, at the opposite sides of its central brace member or partition 6 has a plurality of upwardly extending bolts 26 which are provided with heads that are embedded within the ballast material in the central compartments which are divided by the partition 6. The inner edges of the top sections 21 and 40 45 22 are beveled outwardly, as indicated by the numerals 28, and the numeral 29 designates a dove-tailed wedge member which is adapted to have its inclined sides co-operate with the beveled ends 28 of the top sections 50 55 21 and 22. The beveled member is provided with elongated openings 30 through which the bolts 26 pass, and the numerals 31 designate the nuts for the said bolts.

It is to be understood that the beveled 55 ends 28 of the top plates 21 and 22 are inclined from one of the sides of each of the said plates to the opposite side, so that the dove-tailed slot provided between the said ends is widened at one of the sides of the 60 plates than at the opposite sides, and, as has been stated, the dove-tailed member 29 is wedge-shaped so it will be noted that by adjusting the wedge 29 transversely of the tie the plates 21 and 22 will be forced in a 65 longitudinal direction toward the blocks 18,

so that their lips 23 will be forced tightly into contact with the base flanges of the rails, as illustrated in Fig. 3 of the drawing.

From the above description, taken in connection with the accompanying drawing, the simplicity of the device as well as the advantages thereof will, it is thought, be perfectly apparent to those skilled in the art to which such inventions appertain without further detailed description.

Having thus described the invention, what I claim is:

1. A tie of the class set forth comprising a shell having a central partition and cross brace members arranged between the partition and the ends of the shell to provide the said shell with a plurality of compartments which are adapted to receive a ballast, cushion blocks upon the shell and cross brace members, and said cushions adapted to serve as rests for the rails.

2. A tie for railway rails comprising a metallic shell including a bottom, sides and ends, the shell having a central transverse partition, cross brace members arranged at the opposite sides of the partition to provide the tie with a plurality of ballast receiving compartments, rail receiving cushion blocks received within depressions in the cross members and in the sides of the tie, rail blocks upon the ends of the tie, and top members provided with rail engaging lips secured to the shell.

3. In a tie for railway rails, a shell comprising a body which includes a bottom and sides, and members having their transverse edges flanged and secured to the sides of the shell, the shell having a central transverse partition, cross brace members between the partition and the ends, said cross members having their ends flanged and secured to the sides of the shell, the cross members and partition dividing the shell into a plurality of ballast receiving compartments, the sides of the shell and cross brace members having alining depressions, cushion members within the depressions and adapted to serve as rail receiving seats, and means for retaining the rails upon the seats.

4. In a tie for railway rails, a shell comprising a body which includes a bottom and sides, and members having their transverse edges flanged and secured to the sides of the shell, the shell having a central transverse partition, cross brace members between the partition and the ends, said cross members having their ends flanged and secured to the sides of the shell, the cross members and partition dividing the shell into a plurality of ballast receiving compartments, the sides of the shell and cross brace members having alining depressions, cushion members within the depressions and adapted to serve as rail receiving seats, means for retaining the rails

upon the seats, blocks upon the ends of the shell and removably secured thereto, said blocks having their inner faces shaped to receive the sides of the rails, and adjustable means arranged upon the tie and secured thereto for sustaining the rails upon the cushions and into contact with the blocks.

5. In a tie for railway rails, a shell comprising a body which includes a bottom and sides, and members having their transverse edges flanged and secured to the sides of the shell, the shell having a central transverse partition, cross brace members between the partition and the ends, said cross members having their ends flanged and secured to the sides of the shell, the cross members and partition dividing the shell into a plurality of ballast receiving compartments, the sides 20 of the shell and cross brace members having alining depressions, cushion members within the depressions and adapted to serve as rail receiving seats, means for retaining the rails upon the seats, and means including adjustable rail engaging members for retaining the rails upon the cushion members.

6. A tie comprising a rectangular member having an open top and having brace members of a width equaling the depth of the sides of the tie and secured to the said sides and dividing the tie into a plurality of ballast receiving compartments, rail receiving cushion members arranged upon the tie, rail engaging blocks removably connected with the tie at the top thereof, a pair of

top plates for the tie and adjustably secured thereon, said plates having their outer edges provided with rail engaging lips, and a wedge member also secured upon the top of the tie and adapted to contact with the inner edges of the top plates for moving the said plates toward the rail engaging blocks.

7. A tie comprising a metallic shell having an open top and having a plurality of brace members which divide the interior of the tie into a plurality of compartments, bolts anchored within the compartments and projecting above the tie, cushion members arranged within the tie adjacent the ends thereof and adapted to lie flush with the top of the tie, rail contacting blocks engaged by certain of said bolts and disposed adjacent the cushion members, a pair of top plates having elongated slots through which certain of the bolts pass, said plates having their outer edges formed with rail engaging lips, the inner edges of the plates being inclined and beveled transversely, a dovetailed wedge member having elongated openings through which certain of the bolts pass and adapted to engage with the beveled and inclined ends of the top plates, and nuts for all of the bolts.

In testimony whereof I affix my signature in presence of two witnesses.

OTTO L. WEIMAR.
